UNITED STATES PATENT OFFICE

STERLING H. CAMPBELL, OF ST. LOUIS, MISSOURI, ASSIGNOR TO RAILWAY DEVICES COMPANY, OF ST. LOUIS, MISSOURI, A CORPORATION OF MISSOURI

JOURNAL BEARING FOR RAILWAY CARS

Application filed June 18, 1928. Serial No. 286,086.

My invention relates to a journal bearing for railway cars and particularly to improved means for removing the wedge from the bearing when it is disassembled.

5 In my prior Patent No. 1,204,405 of November 14, 1916, I have shown a form of journal wedge which may be readily removed from the bearing by the use of a hooked tool inserted above the wedge. It is the object 10 of the present invention to so construct a journal bearing, and particularly the wedge thereof, that the wedge may be engaged from below and removed without the use of a special tool.

15 In the accompanying drawings, which illustrate one form of journal bearing made in accordance with my invention, Figure 1 is a vertical longitudinal section through the upper part of a car journal box; Figure 2 is 20 a section taken on the line 2—2 of Figure 3; Figure 3 is an enlarged bottom plan view of the wedge; Figure 4 is a section taken on the line 4—4 of Figure 3; and Figure 5 is a section taken on the line 5—5 of Figure 3.

25 Referring first to Figure 1, the journal box indicated at 1 is of the usual type supported on the axle 2 by means of the brass 3 and wedge 4. The wedge may be of any suitable conformation but is preferably of the 30 general form of the standard M. C. B. wedge so as to be interchangeable therewith. Its upper face 5 is slightly curved in a longitudinal direction to allow the necessary rocking movement relative to the axle. Longitudinal 35 movement of the wedge relative to the box is prevented by contact of the front edge of the wedge with a lug 6 on the box.

The rear end of the brass is provided with an upwardly extending flange 7 which contacts with the rear edge of the wedge and thus holds the front edge of the brass out of contact with a retractile flange on the wedge now to be described.

40 On the front end of the wedge I form a retractile flange or hand-hold 8 extending downwardly and having its lower edge curved on a radius substantially equal to that of the axle flange 9. By so curving the flange 8 I find that interference with the axle flange 45 is avoided and at the same time even in the

smallest size of bearings in use on railway cars sufficient area of flange is provided to form an effective hand-hold by means of which a workman may grasp and withdraw the wedge from the bearing box.

55 In disassembling the parts of the bearing the box is raised by means of a jack or similar device to remove the weight of the car from the axle. As is well known, the wedge will usually adhere to the box so as to be raised with it. Owing to the fact that the front end of the brass is prevented by the flange 7 from contacting with the retractile flange 8 of the wedge, the brass or at least its forward end will remain in contact with the axle, thus dropping away from the wedge and so providing sufficient space between the axle flange 9 and the wedge flange 8 to allow the workman to insert his fingers between these parts and grasp the latter named flange.

60 The curved form of the upper face of the wedge allows of the wedge being readily rocked a sufficient distance to permit disengagement of its forward edge from the lug 6 so that it may be withdrawn from the box.

65 In addition to providing a hand-hold for removing the wedge the curved flange 8 forms an accurate gauge for determining when the brass has reached the limit of its wear and must be renewed.

70 Having fully described my invention, what I claim as new and desire to secure by Letters Patent of the United States is:

75 1. A wedge for journal bearings having a lower face comprising a central horizontal portion adapted to bear on a brass, said wedge having a part extending forwardly of said central portion and carrying hand-hold means positioned laterally of and below said central portion, said means being spaced from the forward end of the brass when the brass and wedge are in assembled relation, and being adapted to form a hand-hold for the removal of the wedge from the journal box.

80 2. A wedge for journal bearings comprising a body portion provided on its under side with a horizontal bearing face and a pair of downwardly projecting side portions adapted to cooperate with a brass, said side portions being provided with recessed forward 85 90 95 100

extensions, the forward walls of said recesses extending below the horizontal bearing face and being spaced from the forward end of the brass when the brass and wedge are in assembled relation, and adapted to form hand-holds for the removal of the wedge from the journal box.

3. A wedge for journal bearings comprising a body portion provided on its under side with a horizontal bearing face to cooperate with a brass and a pair of downwardly projecting side portions each provided with an inclined bearing face, said wedge being provided with a pocket at the front ends of the bearing faces, said pocket extending into the side portions of the wedge, the front wall of said pocket forming a flange connected with both the body and the side portions of the wedge and providing a pair of lateral hand-holds approximately triangular in shape and spaced from the brass when the brass and wedge are in assembled relation.

In testimony whereof, I hereunto affix my signature, this 14th day of June, 1928.

STERLING H. CAMPBELL.
